UNITED STATES PATENT OFFICE.

FREDERICK KIEHLER, OF DETROIT, MICHIGAN, ASSIGNOR TO BRIGGS MANUFACTURING COMPANY, OF DETROIT, MICHIGAN, A CORPORATION OF MICHIGAN.

ADJUSTABLE STRIKER PLATE.

Application filed May 11, 1925. Serial No. 29,502.

This invention relates generally to striker plates and refers more particularly to those designed for use in connection with the movable bolts of vehicle door locks and latches. 5 One of the essential objects of the invention is to provide a striker plate of this type that is adapted to be readily adjusted upon a suitable door jamb without interfering with the usual trimming material of the body for taking up wear and preventing the lock bolt from rattling.

Another object is to provide a novel form of retainer plate that is preferably connected to the striker plate and is adapted to cooperate with a portion of the door jamb for holding the striker plate in adjusted position.

A further object is to provide a common means for securing the striker plate and retainer plate to the jamb.

Still another object is to provide a light and durable construction which can be manufactured at a comparatively low cost.

With the above and other objects in view 25 the invention consists in certain novel features of construction, combinations and arrangements of parts as will be more fully described and particularly pointed out in the appended claims.

In the accompanying drawing:

Figure 1 is a fragmentary side elevation of a door jamb with a striker plate embodying my invention attached thereto.

Figure 2 is a cross sectional view taken 35 on the line 2-2 of Figure 1.

Figure 3 is a perspective view of the striker plate.

Figure 4 is a perspective view of the retainer plate.

Figure 5 is a fragmentary perspective view of the door jamb when the striker plate and retainer plate are removed.

Referring now to the drawing in which like characters of reference designate corresponding parts throughout the several views, the numeral 1 designates a door jamb preferably of a vehicle body. As shown, this jamb is preferably formed of sheet metal and is provided at its front and rear edges

with the oppositely extending lateral flanges 50 2 and 3 respectively.

In order that a swinging door 4 may be held closed against the rear flange 2 of the jamb, I preferably provide a suitable striker plate 5 that is preferably mounted upon the outer face of the jamb. This plate 5 is preferably formed of sheet metal and is preferably provided intermediate its ends with a relatively wide transversely extending opening 6 and a laterally extending 60 tongue 7. As shown, the opening 6 preferably extends from the tongue 7 to the rear edge of the plate and is adapted to register with a transversely extending opening 8 in the jamb 1 for receiving a suitable bolt 9 of a lock carried by the door 4. The tongue 7 preferably extends into the transversely extending opening 8 in the jamb 1 and provides a flat bearing for the bolt 9 while in the registering openings 6 and 8 respectively. To facilitate the movement of the bolt 9 into the registering openings 6 and 8, the striker plate 5 is also preferably provided in advance of the opening 6 with a relatively wide depressed portion 11 which 70 preferably inclines inwardly from the forward edge of the opening 6 to the forward edge of the plate 5 and is received by a suitable depressed portion 12 in the jamb 1.

In order that the striker plate 5 may be 80 readily adjusted transversely of the jamb 1 without interfering with the usual trimming material (not shown) of the vehicle body for taking up wear and preventing the bolt 9 from rattling, the depressed portion 12 in 85 the jamb is preferably channel-shaped and preferably extends from the forward edge of the jamb to the forward edge of the transversely extending opening 8.

Located upon the inner face of the jamb 90 1 is a retainer plate 13 that is preferably channel-shaped in cross section and is provided at its opposite sides with the laterally extending attaching flanges 14. As shown, this retainer plate 13 preferably embraces the depressed portion 12 of the jamb and receives the lateral tongue 7 of the striker plate. The flanges 14 of the retainer

plate are preferably connected to the attaching ears 15 of the striker plate by means of suitable headed elements such as the screws 16 that preferably extend through elongated slots 17 in the jamb 1. The screws 16 preferably extend freely through suitable openings 18 in the attaching ears 15 of the striker plate 5 and through the elongated slots 17 in the jamb and preferably threadedly engage suitable openings 19 in the flanges 14 of the retainer plate 13. Thus, the striker plate 5 and retainer plate 13 may be clamped against opposite sides of the jamb 1 by a common securing means and are capable of moving as a unit when adjusted thereon.

In order that the striker plate 5 may be held in adjusted position, the base 20 of the retainer plate is preferably provided at its rear end with a series of transversely extending corrugations 21 that are adapted to be alternately engaged by a suitable tongue 22 projecting inwardly from the jamb 1 at the rear end of the opening 8. Thus, the arrangement is such that the tongue 22 may be held firmly in engagement with any of the corrugations 21 when the flanges 14 of the retainer plate and the ears 15 of the striker plate are clamped against the jamb by means of the screws 16.

In use, when it is desired to adjust the striker plate 5, the screws 16 are preferably adjusted so that the corrugations 21 of the retainer plate will be disengaged from the tongue 22, whereupon the striker plate 5 and retainer plate 13 may be adjusted as a unit transversely of the jamb 1 to the desired position. The screws 16 may then be adjusted to clamp the plates 5 and 13 against the jamb 40 so that one of the corrugations 21 will engage the tongue 22 for holding the striker plate 5 in adjusted position.

From the foregoing description, it will be readily apparent that the striker plate 5 may be easily adjusted transversely of the jamb 1 without interfering with the usual trimming material (not shown) of the vehicle body. Inasmuch as the screws 16 are capable of securing both the striker plate 5 and the retainer plate 13 to the jamb, it is also apparent that these plates move as a unit and may be held firmly in adjusted position by the tongue 22 when the screws 16 are adjusted to clamp the plates against the jamb. Thus, the device is formed of relatively few parts which may be easily and quickly assembled or taken apart. As a result, the cost of manufacturing such a device has been reduced to a minimum.

While it is believed that from the foregoing description the nature and advantages of the invention will be readily apparent, I desire to have it understood that I do not limit myself to what is herein shown and described, and that such changes may be re-

sorted to when desired as fall within the scope of what is claimed.

What I claim as my invention is:

1. The combination with a jamb having an opening for receiving a bolt, and a depressed portion in advance of the opening, of an adjustable striker plate having an opening registering with the opening in the jamb, and an inclined portion located in the depressed portion of the jamb for guiding the bolt into the registering openings, and means for securing said striker plate to the jamb.

2. The combination with a jamb having an opening for receiving a bolt, and a depressed portion in advance of the opening, of a striker plate adjustably mounted on the jamb having an opening registering with the opening in the jamb, said striker plate also having an inclined portion located in the depressed portion of the jamb for guiding the bolt into the registering openings, and means for holding the striker plate in adjusted position on the jamb.

3. The combination with a jamb, of a projection on the jamb, a striker plate adjustable upon one side of the jamb, a retainer plate engageable with said projection, and a connection between said plates adapted to clamp said retainer plate against the projection aforesaid to hold the striker plate in adjusted position.

4. The combination with a jamb, of an adjustable striker plate upon one side of the jamb, a retainer plate upon the opposite side of the jamb, common means for securing said striker plate and retainer plate to said jamb, and a projection upon said jamb adapted to be engaged by one of said plates for holding both of said plates in adjusted position.

5. The combination with a jamb having a transversely extending opening adapted to receive a bolt, said jamb also having a depressed portion in advance of the opening, of a striker plate having an opening registering with the opening in the jamb for receiving the bolt, said striker plate also having an inclined portion movable in the depressed portion of the jamb for guiding the bolt into the registering openings aforesaid, and means for securing the striker plate to the jamb.

6. The combination with a jamb having an opening extending transversely thereof, and a depressed portion in advance of the opening, of a striker plate slideable on the jamb having a projection movable in the opening in the jamb and having an inclined depressed portion in advance of the projection movable in the depressed portion of the jamb, and means for securing the striker plate to the jamb.

7. The combination with a jamb having an opening therein, of a striker plate adjustable upon one side of said jamb and having

an opening registering with the opening in the jamb, a projection upon the jamb adjacent the opening therein, a retainer plate upon another side of said jamb and having a channel-shaped portion receiving the projection aforesaid, and securing means for said striker plate extending through said jamb and engaging said retainer plate, said

retainer plate having serrations engageable by the projection for preventing movement, 10 of said retainer plate and striker plate relative to said jamb when said securing means is in operative securing position.

In testimony whereof I affix my signature.

FREDERICK KIEHLER.
